PAGE 4

Fig. 4.

Fig. 5.

The back is plain and unadorned.

We claim:

The ornamental design for a triple dresser base, substantially as shown, and described.
